HAND VACUUM CLEANER

John C. Wistrand, St. Paul, Minn., assignor to Brown & Bigelow, St. Paul, Minn.

Application August 12, 1957, Serial No. 47,303

Term of patent 14 years

(Cl. D9—2)

FIG. 1

FIG. 2

FIG. 3

I claim:

The ornamental design of a hand vacuum cleaner, as shown.
